UNITED STATES PATENT OFFICE

LOUIS A. MAXSON, OF CLAREMONT, NEW HAMPSHIRE, ASSIGNOR TO SULLIVAN MACHINERY COMPANY, A CORPORATION OF MASSACHUSETTS

MINING MACHINE

Application filed February 11, 1924, Serial No. 692,176. Renewed November 16, 1927.

My invention relates to mining machines, and more particularly to mining machines of the so-called room and pillar type.

An object of my invention is to provide an improved mining machine. Another object of my invention is to provide an improved mining machine which will be very compact and low and readily controlled. Other objects and advantages of my invention will 10 hereinafter more fully appear.

In the accompanying drawing I have shown for purposes of illustration one form and a modification which my invention may assume in practice.

15 In this drawing,—

Fig. 1 is a plan view with parts broken away of one illustrative embodiment of my invention.

Fig. 2 is a view partially in side elevation 20 and partially in central vertical longitudinal section, the view being taken substantially on line 2—2 of Fig. 1.

Fig. 3 is an enlarged detail sectional view 25 of a portion of the feeding mechanism.

Fig. 4 is a transverse sectional view showing a modification in the construction.

Referring to the drawing and noting first Figs. 1 to 3, it will be observed that the illustrative embodiment of my invention 30 comprises a mining machine having a bottom plate 1 upon which it is slidable during cutting. This bottom plate at the front end thereof supports a motor casing 2, while to the rear of the motor casing is a gear casing 3. Projecting from the front end of the motor casing is a cutter bar which, except for the fact that at its foremost end it has a 35 semicircular portion, might be roughly said to be triangular in shape, this bar being held 40 in any suitable manner rigidly with respect to the body of the mining machine. Herein it will be observed that the guideways 4 for the cutter chain 5 are extended along the side of the motor casing and these extend back 45 for the full length of this casing and to a point to the rear of the front end of the gear casing 3. It will be noted that the cutter chain 5 is guided, adjacent the junction of the cutter bar with the motor casing, by rollers 50 projecting through the bottom of the

guideways 4, these rollers being designated 6. Corresponding rollers are arranged to the rear end of the rear extremities of the guideways 4, these latter rollers being designated 7, while still further to the rear and midway between the rollers 7 there is arranged a cutter chain driving sprocket 8, the plane of the sprocket being the same as the plane of the chain. It will be obvious that, if desired, sprockets could be substituted for the rollers 7, were this desired. Within the motor housing 2 there is a motor 10 having an armature shaft 11 which carries a spur pinion 12. This meshes with a slightly larger spur gear 13 secured to a horizontal shaft 14 55

journaled in bearings 15 and 16 carried upon the bottom plate 1. Between the bearings 15 and 16 the shaft 14 carries a worm 17 whose function will be later described. On the rear end of the shaft 14 is a spur pinion 18 which meshes with a considerably larger spur gear 19 secured to a shaft 20 journaled in bearings 21 upon a partition wall 22 forming a part of the gear casing. The shaft 20 carries a bevel pinion 23 which drives a bevel gear 24 60

which is mounted upon a shaft 25. Connected in non-rotative relation to the gear 24 is a clutch sleeve 26 which is vertically reciprocable by a shipper 27 which is carried by a horizontal shaft 28 journaled as at 29 in a bearing carried by the portion 22 of the housing and extending through a bearing 30 in the rear wall of the gear casing. A handle 31 operates to oscillate the shaft 28 and this is provided with latch means of any suitable 65

type cooperating with a bar 32 to hold the handle 31 in positions for clutching and disengagement of the clutch. The clutch sleeve 26 is provided with clutch teeth 33 adapted to engage with teeth 34 upon a sleeve 35 which is secured in driving relation to the sprocket 8. It will accordingly be apparent that the armature shaft 11 of the motor 10, through the pinion 12, gear 13, shaft 14, pinion 18, gear 19, bevel pinion 23, bevel gear 24 and the clutch mechanism described, drives the cutter chain driving sprocket 8. 70

Now returning to the worm 17, it will be noted that this drives a worm wheel 40 which is journaled upon the abutting ends of a pair 75

of shafts 41 and 42 which together extend completely across the gear casing and is likewise journaled in bearings 43 at its opposite sides. Rigidly connected to the gear, at the opposite sides thereof, are two clutch members 45 and 46 which are adapted to cooperate with clutch teeth 47 and 48 formed on the adjacent sides of transversely slidable clutch members 49 and 50 which are respectively splined to the shafts 41 and 42. It will be observed that, outside of the clutch members 49 and 50, there are arranged stationary bearings 51 and 52 which not only serve as bearings but also as mountings for stationary clutch members 53 and 54 respectively. The clutch members 49 and 50 have teeth 53' and 54' adapted to cooperate with these stationary clutch members. It will further be noted that journaled upon bushings surrounding the shafts 41 and 42 are brake drum members 55 and 56 which are also carriers for gears 57, the latter being rotatably mounted upon studs 58 projecting from the members 55 and 56 (see Fig. 3). In common vertical planes longitudinally extending with the gears 57 are driving pinions 59 respectively secured to the shafts 41 and 42, and enclosing the pinions 57 and 59 are larger internal gears 60 and 61, the gear 60 cooperating with the pinions 57 and 59 which form a part of the driving mechanism associated with the shaft 41. These internal gears 60 and 61 carry tubular shafts 62 and 63 respectively which at their outer ends carry pinions 64 and 65 respectively, and the latter are arranged in driving relation with internal gears 66 and 67 formed herein integral with the interior peripheries of rope winding drums 71 and 72. Cooperating with the brake drum members 55 and 56 are brake bands 73 and 74 held against rotation by any suitable means and having mechanism generally designated 75, and which may be of any suitable form, but which is herein shown as including oppositely threaded portions upon rods 76 cooperating with nuts 77 and 78 secured to the opposite extremities of the brake band, the rods 76 being provided with handles 79 and 80, at the rear end of the machine for permitting their operation. For the purpose of shifting the clutch members 49 and 50 there are journaled upon suitable projections 81 and 82 clutch shifter members 83 and 84 to whose forwardly projecting arms there is pivotally connected a link 85, which link is adapted to be reciprocated in opposite directions by a bell crank lever 86 whose oscillation is secured by a rod 87 extending out through the rear end of the machine and provided with a handle 88, there being provided any suitable means of any desired type for holding this rod in its several positions of adjustment. It will be observed that a machine of the type illustrated may cut in opposite directions if this be desired. Herein

I have shown guiding sheaves for the cables 90 and 91 respectively associated with the drums 71 and 72, these sheaves being designated 93 and 94 and arranged respectively at the front left hand and rear right hand corners of the machine looking forward, but it will be understood that corresponding sheaves may be arranged, if desired, at the remaining corners if it is desired to cut in the opposite direction. The cutter chain is guarded by box-like covers 95 where it passes along the side of the motor housing and runs within spaces provided within the gear casing housing.

From the foregoing description the mode of operation of the mechanism will be readily apparent. The operation of the cutter chain driving sprocket has already been described and need not be repeated. When cutting from right to left, it will be observed that the worm 17 rotates clockwise when viewed from the rear, causing a counterclockwise rotation of the worm wheel 40 in Fig. 2. This causes, when the clutch 50 is thrown to cause engagement of the teeth 46 and 48, counterclockwise rotation of the shaft 42 and a corresponding counterclockwise rotation of the pinion 59 which is secured thereon. When the brake band 74 is applied, it will be evident that the corresponding gear 57 will be held against bodily motion and will simply drive the gear 61 in a clockwise direction and this will result in driving of the corresponding pinion 65 in a clockwise direction and so rotation of the drum 72 in a clockwise direction with resultant winding in of the leading cable 91. It will be noted that by virtue of the construction shown, when the clutch teeth 46 and 48 are engaged, the clutch teeth 53' and 54' are engaged and so the shaft 41 is held positively against rotation. As a result, if the brake band 73 is held tight, the drum 71 will be incapable of rotation, but by allowing the drum 73 to slip, it will be readily possible to secure any desired rate of paying out of the tail rope 90.

Now referring to Fig. 4, it will be noted that a modified construction has been disclosed in which the guide rollers 7 may be omitted and in which two driving sprockets 101 and 102 may be employed. In this form it will be noticed that a gear 103 is supported and journaled by means (not shown) for rotation relative to the gear 24. The gear 103 meshes with gears 104 and 105 respectively operatively connected in driving relation with the cutter chain driving sprockets 102 and 101. A clutch 106 is arranged with pins 107 adapted to be projected through the gear 24 and into openings (not shown) in the gear 103 for the purpose of clutching the gear 103 to the gear 24 when driving of the cutter chain is desired. This construction provides one less angle in the cutter chain and a double sprocket drive therefor.

It will be observed that in both species truck driving means driven from the gear 24 may be provided and such mechanism is shown at 108 in Fig. 2. At 110 is shown a handle for operating a suitable motor controller and reverse mechanism which is not shown, but which may be arranged in the space available for this purpose directly forward from this handle, though it will be evident that there are other spaces in which it might be put.

While I have in this application specifically described one form and a modification which my invention may assume in practice, it will be understood that this form of the same and the modification thereof are shown for purposes of illustration and that the invention may be modified and embodied in various other forms without departing from its spirit or the scope of the appended claims.

What I claim as new and desire to secure by Letters Patent is:

1. In a room and pillar mining machine, a cutter chain, means for guiding the same for circulation in an orbit, and means for driving the same including a motor whose projection on a horizontal plane lies entirely within the projection on such plane of the inner edge of the orbit of the cutter chain, the height of said motor substantially determining the height of the machine.

2. In a mining machine, a cutter chain, means for guiding the same for circulation in an orbit, and means for driving the same including a motor whose projection on a horizontal plane lies entirely within the projection on such plane of the inner edge of the orbit of the cutter chain and which is cut by a horizontal plane passing through the cutter chain.

3. In a mining machine, a cutter chain, means for guiding the same in an orbit, and means for driving the same including a motor whose bottom lies inside the orbit and below the top thereof.

4. In a mining machine, a cutter chain, means for guiding the same in an orbit, and means for driving the same including a motor whose bottom lies inside the orbit and substantially on the bottom of the mine.

5. In a room and pillar mining machine, a projecting cutter bar, a motor, the height of said motor substantially determining the height of the machine and a cutter chain circulating around the periphery of the cutter bar and of the motor and driven by the latter.

6. In a room and pillar mining machine, a motor having a horizontal, longitudinally extending armature shaft, a shaft driven thereby parallel thereto and below and to the rear thereof, cutter chain driving mechanism driven from the rear end of said shaft, and feeding mechanism for feeding said machine upon its bottom upon the mine bottom during cutting including a feed operating member

having flexible feeding means cooperating directly therewith and a driving element driven by said second mentioned shaft forward of the rear thereof and rotatable on an axis above said shaft.

7. In a room and pillar mining machine, a motor having a horizontal, longitudinally extending armature shaft, a shaft driven thereby parallel thereto and below and to the rear thereof, cutter chain driving mechanism driven from the rear end of said shaft, and feeding mechanism for feeding said machine upon its bottom upon the mine bottom during cutting including a feed operating member having flexible feeding means cooperating directly therewith and a driving element driven by said second mentioned shaft between the ends thereof and rotatable on an axis transverse to and above said shaft.

8. In a room and pillar mining machine, a motor having a horizontal, longitudinally extending armature shaft, a shaft driven thereby parallel thereto and below and to the rear thereof, cutter chain driving mechanism driven from the rear end of said shaft, and feeding mechanism including a pair of feed operating members each adapted to cooperate directly with flexible feeding means and disposed one at each side of said machine and actuating means therefor rotating on a transverse axis above and between the ends of said second mentioned shaft and driven thereby at a point between the ends of the latter.

9. In a mining machine, a cutter bar, a motor, and motor driven feeding means including a pair of shafts adapted to be driven by said motor or held stationary, clutch means for connecting said shafts to the motor, stationary means, said clutch means being also operative to connect said shafts to said stationary means, brake controlled transmission mechanisms operatively connected to said shafts, and feed operating members connected to said transmission mechanisms and each adapted to cooperate directly with flexible feeding means.

10. In a mining machine feeding mechanism, a motor, a pair of members operative on rotation in one direction to pull in and on rotation in the opposite direction to pay out flexible feeding means, flexible feeding means associated with said members, and means for controlling said members including two aligned shafts, means for connecting said shafts to said motor or holding them stationary, members operative on rotation to rotate said first mentioned members, driving members carried by said shafts, and power transmission elements between said driving members and said second mentioned members rotatable on axes offset from the axes of said shafts.

11. In a mining machine feeding mechanism, a motor, a pair of members operative on rotation in one direction to pull in and on ro-

tation in the opposite direction to pay out flexible feeding means, flexible feeding means associated with said members, and means for controlling said members including a pair of shafts, means for connecting said shafts to said motor or holding them stationary, members operative on rotation to rotate said first mentioned members, driving members carried by said shafts, and power transmission elements between said driving members and said second mentioned members, said power transmission elements being mounted on manually controllable rotatable members.

12. In a mining machine feeding mechanism, a motor, a pair of members operative on rotation in one direction to pull in and on rotation in the opposite direction to pay out flexible feeding means, flexible feeding means associated with said members, and means for controlling said members including a pair of shafts, means for connecting said shafts to said motor or holding them stationary, members operative on rotation to rotate said first mentioned members, driving members carried by said shafts, and power transmission elements between said driving members and said second mentioned members, said power transmission elements being mounted on frictionally controllable rotatable members.

13. In a mining machine, a cutter bar by which cutting devices are carried, a motor for actuating the cutting devices including a motor casing, and means for guiding the cutting devices including means carried directly by the exterior of said motor casing and guiding said chain along said casing.

14. In a mining machine, a cutter chain adapted to be circulated in an orbit, and means for actuating said cutter chain including a horizontally disposed motor disposed within and projecting below the orbit of said chain.

15. In a mining machine, a driving motor having a motor casing adapted to rest substantially on the mine bottom, and cutting mechanism driven by said motor including a cutter chain arranged and guided to be circulated about said casing.

16. In a mining machine, a cutter chain adapted to be circulated in an orbit, a driving motor for said cutter chain disposed within and extending below the orbit of said cutter chain, and feeding means driven by said motor including feed and takeup members and flexible feeding means cooperating with said members.

17. In a mining machine, a motor, the height of the machine being substantially determined by the height of the motor, a cutter chain extending longitudinally of said motor and guided directly on the casing thereof, and means driven by said motor for actuating said cutter chain.

18. In a mining machine, a machine frame, a cutter chain, means for guiding said cutter chain on each end of said machine frame and

about which the chain is adapted to be circulated in a norbit, and means for driving said chain including a motor disposed within and partially below the top plane of the orbit of said chain.

19. In a mining machine, a motor having its power shaft extending longitudinally of the machine, a shaft driven by said motor shaft parallel to the latter and below and to the rear thereof, cutting mechanism driving mechanism driven from the rear end of said shaft, and feeding mechanism including a driving element driven by said shaft forward of the rear thereof and rotatable on an axis above said shaft and a feed operating member driven by said driving element and adapted to cooperate directly with flexible feeding means.

20. In a mining machine, a machine frame, a motor carried thereby and having with respect to the length of the machine frame forward and rear ends, a cutter bar carrying cutting devices and projecting forwardly from said frame at the end of the latter near the forward end of the motor, and driving mechanism for the cutting devices driven from the rear end of said motor and comprising a sprocket rotatable in a horizontal plane between the vertical limits of said motor.

21. In a mining machine, a machine frame, a motor, the overall height of the machine being substantially determined by the height of the motor, a cutter bit carrying cutter bar projecting forwardly from said frame and having its uppermost and lowermost surfaces lying in planes intersecting said motor, said motor having forward and rear ends, the latter the more remote from the portion of said frame at which said cutter bar projects, and means for actuating the cutter bits including a sprocket driven by the rear end of said motor.

22. In a mining machine, a machine frame, a motor, the overall height of the machine being substantially determined by the height of the motor, a cutter bit carrying cutter bar projecting forwardly from said frame and having its uppermost and lowermost surfaces lying in planes intersecting said motor, said motor having forward and rear ends, the latter the more remote from the portion of said frame at which said cutter bar projects, means for actuating the cutter bits including a sprocket driven by the rear end of said motor, and feeding means driven by the rear end of said motor.

23. In a mining machine of the type which is slidable upon the mine bottom during cutting, a motor whose vertical dimension is substantially identical with the overall height of the machine, cutting mechanism driven thereby, flexible feeding means for the machine including a plurality of relatively rotatable feed operating and controlling members, each adapted to cooperate with flexible

feeding means, and means including a common operating element for each of said members for selectively effecting rotation of said members or resisting rotation thereof.

5 24. In a mining machine, a motor having its casing slidable directly on its bottom on the mine bottom, the height of which substantially determines the height of the machine, cutting mechanism including transmission means and a cutter chain driving sprocket driven by the rear end of said motor, and feeding means comprising a plurality of feed operating members each adapted to cooperate directly with flexible feeding means adapted 10 to be driven from said cutting mechanism transmission means.

20 25. In a mining machine, a motor having its casing slidable directly on its bottom on the mine bottom, the height of which substantially determines the height of the machine, cutting mechanism driven thereby comprising a cutter chain sprocket driven from the rear end of said motor, and feeding means for the machine disposed intermediate said 25 motor and said sprocket and including a plurality of feed operating members each adapted to cooperate directly with flexible feeding means.

30 In testimony whereof I affix my signature.
